UNITED STATES PATENT OFFICE.

JOHN M. PITCHER, OF SUGAR CREEK, INDIANA.

SPARK-ARRESTER.

SPECIFICATION forming part of Letters Patent No. 330,420, dated November 17, 1885.

Application filed March 31, 1885. Serial No. 160,733. (No model.)

To all whom it may concern:

Be it known that I, JOHN M. PITCHER, of the town of Sugar Creek, and State of Indiana, have invented certain new and useful Improvements in Spark-Arresters, of which the following is a specification.

The object of my invention is to provide means for arresting the sparks issuing from furnaces for heating locomotive, portable, and stationary steam-boilers. I accomplish this object by means of the device described in this specification, and illustrated in the drawings filed herewith, and made a part hereof.

Referring to the drawings, in which similar letters of reference relate to similar parts of my invention, Figure I is a side view of a boiler with my device attached. Fig II is a vertical cross-section of Fig. I, on the line X X. Figs. III and IV represent modifications of the spark-arrester, in sectional view, as applied in Fig. I.

In Fig. I, *b* indicates in dotted lines the boiler, with the ordinary fire-box, *fb*, bridging *bb*, and flues *fl*.

d is a drum or jacket, constructed of sheet or boiler iron, of any desired strength, and made in three sections. The central section, *a*, is a plain cylinder. The two end sections, *a'*, are conical. These sections are firmly riveted together to form a steam-tight casing around the boiler, when attached thereto at the two ends, as indicated in the drawings, and supported by a suitable frame.

C is a collar attached to the boiler over bridging-chamber *bb*, and *C'* is a collar attached to the top of section *a'* of drum *d*, to receive the spark-arrester *sp*, which consists of three sections of pipe, 1, 2, and 3. Section 1 of said pipe fits over collar *C* and receives the sparks and smoke from the bridging-chamber *bb*, as indicated by the arrows, discharging the same into section 2 of the arrester, through which the sparks and smoke pass and discharge into the chamber *ch*.

Sections 1 and 2 of my spark-arrester may be connected at the upper ends, as indicated in Figs. I, III, or IV. In either case a discharge-pipe, 3, is so arranged that one half thereof extends over ascending section 1, and the other half over the descending section 2, of the spark-arrester, as shown by the various relative figures.

cp is a cap made to fit over the top of section 3, provided with a hinge, by means of which it is opened and closed at will.

55

c is a smoke-stack attached to section *a'* of drum *d*, and communicating with chamber *ch*.

st is an exhaust-steam pipe through which steam or air is injected into the bridging-chamber *bb*. The chamber *ch* is so adjusted 60 as to leave a larger space above than below the boiler, as indicated in Fig. II.

The ascending section of my spark-arrester *sp* is placed over and perpendicular to the bridging-chamber *bb*, and joined to the descending section 2 at the upper end. Section 2 inclines downward and connects with chamber *ch* of drum *d*. Sections 1 and 2 connect with section 3, which is so arranged as to project half over the ascending and half over the descending sections, and is provided with a hinged cap, *cp*, which can be opened and closed at will.

The space between sections 1 and 2 of said spark-arrester is covered by a concave sheet. 75 (See Figs. III and IV.)

The method of operating my device is as follows: Before firing up I open the cap *cp*, which allows the smoke to issue through section 3 of my arrester. When sufficient steam 80 has generated to set the machinery in motion, the cap *cp* is closed and the exhaust-steam is injected into chamber *bb* through steam-pipe *st*, creating a draft, which forces the smoke and sparks up through section 1 of my spark-arrester, and down through section 2 and into chamber *ch*, as indicated by the arrows.

In practice I prefer one of the various devices shown on the drawings; but I do not wish to confine myself to this construction of 90 my spark-arrester, as it is obvious that any arrangement for conducting the live sparks and smoke from chamber *bb* into chamber *ch* will accomplish the same object in a more or less satisfactory manner without departing from the spirit of my invention.

The advantages I derive from the use of my invention are as follows: I effect a saving of a large per cent. of fuel, and avoid the danger attending the use of boilers not provided with 100 my device—an object greatly to be desired.

Having thus described my invention, its purposes and advantages, what I claim as new, and desire to secure Letters Patent, is—

1. In a spark-arrester where exhaust-steam is employed for creating a draft, a drum or jacket so arranged as to form a chamber around boilers, in combination with any device for conducting smoke and cinders from fire-places with steam or atmosphere, substantially in the manner and for the purpose set forth.
2. In a spark-arrester for steam-boilers, the combination of the drum or jacket *d*, made in three sections, the central section of which is cylindrical and the two end sections conical-shaped, with steam-pipe *st*, smoke-stack *c*, and spark-arrester *sp*, substantially in the manner and for the purpose set forth.
3. A spark-arrester consisting of drum or

jacket *d*, with its collars *C* and *C'*, a spark-arrester, *sp*, consisting of three sections, 1, 2, and 3, and a hinged cap, *cp*, to form a conductor from chamber *bb* to chamber *ch*, and steam-injecting pipe *st*, all constructed and combined as illustrated in the drawings and described in the specification, substantially in the manner and for the purpose set forth.

In witness whereof I have hereunto set my hand and seal, at Indianapolis, Indiana, this 25th day of March, A. D. 1885.

JOHN M. PITCHER. [L. S.]
